UNITED STATES PATENT OFFICE.

JAMES M. SAWYER, OF CHAPLIN, CONNECTICUT.

SECTIONAL BOAT.

Application filed July 7, 1924. Serial No. 724,616.

To all whom it may concern:

Be it known that I, JAMES M. SAWYER, a citizen of the United States, residing at Chaplin, in the county of Windham and State of Connecticut, have invented certain new and useful Improvements in Sectional Boats, of which the following is a specification.

This invention relates to sectional boat structures, and it consists in the novel features hereinafter described and claimed.

An object of the invention is to provide a boat especially adapted to be used for fishing and hunting and which is composed of sections adapted to be separated from each other and nested one within the other in order that the boat structure may be compactly assembled for storage, transportation or other purposes.

A further object of the invention is to provide a boat of the character stated, consisting of sections adapted to be fitted together in a water tight manner and when set up may be left in the water for an indefinite period of time. When the sections of the boat are nested one within the other, the complete structure may be placed within a suitable casing, and the said casing may be conveniently carried upon an automobile machine, thereby serving as an accessory of the machine, to extend its attractiveness as a sporting appliance.

In the accompanying drawings:

Figure 1 is a top plan view of the boat.

Figure 2 is a bottom plan view thereof. Figure 3 is a side elevation thereof.

Figure 4 is a top plan view of the boat, showing the sections thereof nested one within the other.

Figure 5 is a detailed sectional view through one of the sections of the boat.

Figure 6 is a detailed sectional view of the means for securing the sections of the boat together.

Figure 7 is a side elevation of the casing adapted to receive a boat.

Figure 8 is an edge elevation of a cover for the casing.

The boat comprises sections which are indicated 1, 2, 3, 4, 5, 6, 7 and 8. These sections are bound by angle flanges 9 and the side walls of the sections may be of wood,

papier mâché, or any other suitable material. Each of these sections is provided at its end with upstanding flanges 10, the flanges 10 of one section adapted to be positioned opposite the flanges 10 of the next adjacent section, and packing strips 11 of rubber or other suitable material are interposed between the adjacent flanges 10. The lower ends of the flanges 10 are offset to be received in recesses provided in the outer surfaces of the sections and fastening elements 20 hold the offset portions in place in the recesses. Screw bolts 12 pass transversely through the flanges 10, and nuts 13 are screwed upon the bolts whereby the said flanges are drawn toward each other, and in close contact with the packing strips 11. Certain of the sections of the boat may be provided with cross seats, and if desired, the boat may be propelled by an outboard motor, which may be applied to the stern section in a usual manner. When the sections are disconnected from each other, they may be nested one within the other as shown in Figure 4 of the drawing, and the nested section may be placed in a casing 14, having a lid 15. The lid 15 is provided with a hasp 16 adapted to engage a lock 17 carried by the casing 14 and the casing 14 is provided with a strap 18, which may be connected with the frame of an automobile machine, whereby the casing of the boat may be secured to the automobile machine during transportation.

Having described the invention, what is claimed is;

1. A boat comprising a plurality of sections having at their edges recesses, flanges provided with angular extensions seated and fixed in the recesses, and bolts for holding the flanges together.

2. A boat including a plurality of sections having recesses at their edges, upstanding flanges at the edges provided with offset angular extensions disposed and fixed in the recesses, packing strips disposed between the upstanding flanges, and bolts passing transversely through the upstanding flanges and the packing strips.

In testimony whereof I affix my signature.

JAMES M. SAWYER.
